CLAIM

The ornamental design for an electronic device screen cover, as shown and described.

DESCRIPTION

FIG. 1 is a front, top and left side perspective view of an electronic device screen cover showing my new design in an environment of use;

FIG. 2 is another front, top and left side perspective view thereof;

FIG. 3 is a back, bottom and left side perspective view thereof;

FIG. 4 is a back elevation view thereof;

FIG. 5 is a front elevation view thereof;

FIG. 6 is a left side elevation view thereof;

FIG. 7 is a right side elevation view thereof;

FIG. 8 is a top plan view thereof;

FIG. 9 is a bottom plan view thereof;

FIG. 10 is a back elevation view thereof, shown in an environment of use;

FIG. 11 is an enlarged view thereof, taken from FIG. 10; FIG. 12 is another front, top and left side elevation view thereof, shown in an environment of use; and,

FIG. 13 is an enlarged view thereof, taken from FIG. 12.
